UNITED STATES PATENT OFFICE.

ALBERT DIDIER DELAVIERE, OF PARIS, FRANCE.

TOOL FOR AFFIXING METAL TAGS TO LACES.

SPECIFICATION forming part of Letters Patent No. 311,571, dated February 3, 1885.

Application filed December 20, 1884. (No model.) Patented in France June 9, 1884, No. 162,640.

To all whom it may concern:

Be it known that I, ALBERT DIDIER DELAVIERE, of the city of Paris, France, have invented an Improved Tool for Affixing Metal Tags to Laces and for other Similar Purposes, of which the following is a full, clear, and exact description, and for which I obtained Letters Patent in France for fifteen years, dated June 9, 1884, No. 162,640.

10 The ends of boot and corset laces, and especially braided laces, whether flat or round, are generally sheathed in a small sheet-metal tube (called a tag) for the purpose of preventing the unraveling of the lace and facilitating 15 the threading of the lace through the eyelets of the corset or boot.

This invention has for its object an improved tool for affixing the tag to the lace.

Figure 1 of the accompanying drawings 20 represents a plan view of the tool, (full size.) Fig. 2 represents a side view of the end farthest from the lever, the tool being inverted. Fig. 3 represents in side view on a larger scale the working parts of the machine in position 25 for rolling or wrapping the sheet metal round the lace, the lace and the metal being in section. Fig. 4 represents the same parts in the position assumed at the completion of the operation.

30 The tool consists of a steel bed-block, *a*, provided with ears *b* for fixing it on a bench or other support, a sliding jaw, *c*, and a lever, *d*, operating this slide. The block *a* is recessed to form a fixed jaw, as shown in elevation in 35 Figs. 2, 3, and 4, and the whole of this recessed space is entirely accessible from the side to allow the introduction of the piece of sheet metal and the lace. The slide *c* works between two dovetailed gibbs, *e*, and slides over 40 the surface *g* of the bed-block. The block is rabbeted at *h*, and the part *i* between *g* and *h* is hollowed out in the shape of a semi-cylinder to form the fixed jaw. The slide is provided 45 with a correspondingly-hollowed jaw, *j*, and an extension, *k*, at the upper side, equal in length to *h*, and sliding over it when the semi-cylindrical jaws *j* and *i* come together and form a cylindrical space. The lever *d* is pivoted on a stud, *l*, fixed to the block *a*, and it has a slot, 50 *m*, which receives a pin, *n*, fixed on the slide *c*, whereby a to-and-fro motion is imparted to the latter by the oscillation of the lever.

The mode of using the tool is as follows:

The slide is drawn back as in Fig. 3, the piece of metal *o*, cut to size, is placed on the surface *g*, one of its longitudinal edges being close up to the hollow *i*, and the lace *p* placed on this piece of metal and in the hollow *i*. The slide *c* is then brought quickly forward by means of the lever, the lower acute edge of the hollow *j* passing beneath the plate *o*. The plate *o* being thus pressed edgewise between the two semi-cylindrical jaws, and being prevented from escaping by the part *k*, is bent into the form of a cylindrical tube corresponding 65 to the surfaces *i* and *j* and imprisoning within it the end of the lace, as shown in Fig 4.

The operation is very simple, and perfect tags may be obtained if care be taken to properly proportion the width of the sheet of 70 metal to the development of the surface of the two semi-cylindrical jaws *i* and *j*.

I have shown in Figs. 5 and 6 a similar tool slightly modified in detail.

In Figs. 1, 2, 3, and 4 the pin *n* of the slide 75 *c* is fixed near the rear end of the slide, and therefore when the slide is drawn back the pressure of the hand on the lever tends to cant the slide, which is objectionable. To remedy this defect the pin *n* is fixed near the working end of the slide so that the pressure of the hand cannot tend to raise this part, being always applied directly over this point. In this case the lever *d* is made of curved form, as shown in Fig. 5, in order that its 85 handle shall be at right angles with the block when the slide is in its forward position, as the maximum effective leverage is thus obtained at the point where it is required.

Fig. 5 is a top view, and Fig. 6 is a side view, the lever being in section.

The lever *d* is of bent form, and the slot *m*, which receives the pin *n*, stands obliquely to the line of the handle, and the pinion *n* is fixed near the working end of the slide *c*. 95

The other parts of the tool being the same as before, no further description is necessary.

The essential feature of my invention, which renders the working of the tool very simple and easy, is the combination of the slide and the lever.

By changing the form of the working parts of the tool it may be employed for other operations than affixing tags—for instance, for perforating and joining different pieces. 105

I claim—

A tool for affixing tags and for other purposes, consisting, essentially, of a slide, *c*, recessed at *j* and provided with extension *k*, a block, *a*, having a semi-cylindrical hollow, *i*, 5 and the surface *h*, and a lever, *d*, pivoted at *l*, and having a slot, *m*, engaging with a pin, *n*, for imparting motion to the slide *c*, substantially as shown and described.

The foregoing specification of my improved tool for affixing metal tags to laces and for other similar purposes signed by me this 19th day of November, 1884.

ALBERT DIDIER DELAVIERE.
